(57) **CLAIM**

The ornamental design for a pacifier as shown and described.

DESCRIPTION

FIG. 1 is a front perspective view of a pacifier showing my new design;

FIG. 2 is a top view thereof;

FIG. 3 is a right side view thereof;

FIG. 4 is a left side view thereof;

FIG. 5 is a front view thereof;

FIG. 6 is a rear view thereof; and,

FIG. 7 is a rear perspective view thereof.

In the drawings, the equal-length broken lines depict portions of the pacifier that form no part of the claimed design.

1 Claim, 7 Drawing Sheets
